[57] ABSTRACT

An open flame gas burner has a body portion bringing the gas to a perforated tip. The top screws onto the body and clamps a bottom screen between it and the body extending in a plane at right angles thereto. The bottom screen is circular and two interfitted spaced inner and outer cup-shaped screen members over the tip are supported by the lower screen whose periphery is turned over to engage extending peripheral edges of the cup-shaped screens.

OPEN FLAME BURNER

BACKGROUND OF THE INVENTION

The present invention relates to open flame gas burners of the type suitable for use in street lighting or for residential lighting purposes where an open flame is desired for esthetic purposes. The burners of the present concept are relatively windproof and are not easily extinguished by wind gusts. These burners are particularly suitable for use in ornamental exterior lamps subject to all sorts of weather where regular service is impractical and the burners remain lighted day and night. The elements of the burner are so disposed as to baffle gusts of wind and prevent extinguishing of the flame.

Generally, the present invention relates to combustion with porous, capillary, particulate or sievelike flame holders in which woven wire screens hold the flame. Representative prior art patents are U.S. Pat. Nos. 2,961,850; 3,219,025; and 3,391,683.

SUMMARY OF THE INVENTION

It is therefore the object of the present invention to provide a novel windproof open flame burner for use in exterior domestic or public light fixtures or lamps comprising a body having a gas passage therein, a tip having burner openings therein mounted on the body and receiving gas therefrom, a circular flat bottom screen clamped between the tip and the body and inner and outer spaced cup-shaped screens surrounding the tip and mounted on the bottom screen, the periphery of the bottom screen being turned over onto flat peripheral flanges of the inner and outer screens holding the assembly together. An ornamental cup may be mounted on the body and extend upwardly and outwardly adjacent to and around the bottom screen.

BRIEF DESCRIPTION OF THE DRAWINGS

In the accompanying drawings in which like reference characters indicate like parts,

FIG. 1 is an elevational view, partly in section, of a preferred embodiment of the present invention;

FIG. 2 is a view from above of the bottom screen and tip of FIG. 1 before assembly with the inner and outer screens; and

FIG. 3 is a partial sectional view of the bottom screen prior to assembly.

DESCRIPTION OF THE PREFERRED EMBODIMENT

Referring now to the drawings, the body for the burner is shown at 10 and has central duct 11 therein for the flow of gas to tip 12, tip 12 having burner openings 13 therein. Tip 12 is provided with threaded portion 14 received in threaded opening 15 in body 10. Body 10 may be threaded at 16 for connection to gas cock 17 which adjusts the flow of gas to tip 12 and thus regulates the size of the flame.

A circular bottom screen 18 has circular central opening 19 receiving threaded portion 14 to clamp screen 18 between tip 12 and body 10. Screen 18 has upturned peripheral wall 20, FIG. 3, the purpose of which will hereinafter appear.

An inner cup-shaped screen 21 has a peripheral flat rim 22 which is received in screen 18 with screen 21 then spaced from and covering tip 12.

An outer cup-shaped screen 23 has a peripheral flat rim 24 which is received in screen 18 on top of rim 22 with screen 23 then spaced from and covering screen 21.

With inner screen 21 and outer screen 23 thus placed, wall 20 is then turned in on rim 24 at 25 and the burner is maintained in assembled condition.

An ornamental cup 26 may be secured between body 10 and cock 17 and extends upwardly and outwardly to surround in spaced relation the assembled screens as above-described. Cup 26 may be disposed to deflect upward drafts of air.

This embodiment is lighted by opening cock 17 to permit flow of gas through opening 13. The gas is lit by extending a flame adjacent outer screen 23 and a gas flame is formed extending upwardly and outwardly from tip 12.

It has been found that the arrangement of screens 18, 21 and 23 as above-described so baffle any currents of air or gusts of wind infringing on the burner from any direction as to prevent extinguishing of the flame even for wind velocities in the neighborhood of 30 miles per hour.

The size of the mesh for screens 18, 21 and 23 should be commensurate with the actual dimensions of the screens, screen 18 having an internal diameter of about 1 1/4 inches, screen 21 having an internal diameter of about nine-sixteenths inch and screen 23 having an internal diameter of twenty-seven/thirty-second inch. A screen mesh from 36 to 24 mesh has been found to be acceptable and a mesh of about 30 with wire diameter of 0.012 inch is used with the embodiment of the invention described above.

What I claim is:

1. A windproof open flame burner comprising a body, a passage for gas in said body, a tip mounted on said body communicating with said passage, burner openings in said tip, a circular flat bottom screen mounted between said tip and said body, an inner cup-shaped screen mounted on said bottom screen and covering and spaced from said tip, an outer cup-shaped screen mounted on said bottom screen and covering and spaced from said inner screen and means for connecting said inner and said outer screens to said bottom screen.

2. A burner as described in claim 1, said means including a first flat peripheral rim on said inner screen engaging said bottom screen, a second flat peripheral rim on said outer screen engaging said first rim and an upturned and inturned peripheral rim on said bottom screen engaging said second rim and clamping said screens together.

3. A burner as described in claim 1, including an ornamental cup secured to said body and extending upwardly and outwardly therefrom and surrounding said screens in spaced relation thereto.

4. A burner as described in claim 1, said screens having a mesh size of from 24 to 36.

5. A burner as described in claim 3, including a gas cock secured to said body, said ornamental cup being mounted between said body and said cock.
